(57) **CLAIM**

The ornamental design for crusher block for particulate size reduction system, as shown and described in the attached specification.

DESCRIPTION

FIG. 1 is a top view of a crusher block in accordance with the present disclosure, showing the flange with a pair of bores for attachment with the yoke assembly;

FIG. 2 is a front elevation view of a crusher block of FIG. 1 in accordance with the present disclosure, showing the inboard face for cooperating with swing hammers;

FIG. 3 is a side elevation view of the crusher block of FIG. 1 in accordance with the present disclosure, showing the elevation of the slot for accommodating tabs of side supports;

FIG. 4 is a bottom view of the crusher block of FIG. 1 in accordance with the present disclosure, showing the slots for accommodating tabs of side supports;

FIG. 5 is a top view of the crusher block of FIG. 1 in accordance with the present disclosure, showing in broken lines an adjustment mechanism connected to a yoke assembly, which is joined directly to the crusher block; and,

FIG. 6 is a cross-sectional side elevation view of the crusher block assembly of FIG. 5 in accordance with the present disclosure, showing in broken lines an adjustment mechanism connected to a yoke assembly, which is joined directly to the crusher block, wherein the cross-section is taken at the location indicated in FIG. 5.

The broken lines in FIGS. 5 and 6 are for illustrative purposes only, to show the crusher block in its environment, and form no part of the claimed design.
